UNITED STATES PATENT OFFICE.

PETER DUNLAP GRAHAM, OF CORUNNA, INDIANA.

HAND-PLOW.

SPECIFICATION forming part of Letters Patent No. 417,169, dated December 10, 1889.

Application filed April 20, 1889. Serial No. 207,953. (No model.)

To all whom it may concern:

Be it known that I, PETER DUNLAP GRAHAM, a citizen of the United States, residing at Corunna, in the county of De Kalb and 5 State of Indiana, have invented a new and useful Hand-Plow, of which the following is a specification.

My invention relates to that class of hand-plows in which the height of the handle may 10 be varied to suit the convenience of the operator, and the standard carrying the shovel or cultivator-blade may be adjusted to run deep or shallow, as may be desired.

The objects of my invention are, first, to provide a hand-plow in which there is no wide 15 frame, spreading handles, or laterally-projecting parts to prevent working up close to the roots of large spreading plants; second, to provide an adjustable hand-plow which 20 may be more cheaply manufactured, be lighter, and more simple in its construction than those in common use; third, to provide a hand-plow which may be constructed mainly of wood, in order to secure the least weight 25 and the least expense in manufacture, and yet possess sufficient strength and rigidity 30 and be of such construction that all shrinkage of the timber may be readily taken up, so that it will not be liable to become loose 35 and rickety on account of age and use. I attain these objects by means of the mechanism illustrated in the accompanying drawings, in which—

Figure 1 is a side elevation which embodies 35 my invention complete. Fig. 2 is a top view of the rear portion of the implement, showing the manner of attaching the cross-head, &c. Fig. 3 is a side view of the wheel; Fig. 4, the same as Fig. 3, except that it shows a slight 40 variation in the construction of the hub, as will be hereinafter more fully explained.

In view of the illustrations given, it will be seen that my invention consists, simply, of the two side bars A A, having the supporting-wheel B pivoted between their front or 45 lower ends, a cross-head or hand-hold C, attached to their rear or upper ends, and the standard D, clamped between the side bars A A a short distance in the rear of the wheel 50 B. This construction may be varied somewhat by allowing the side bars A A to extend only a short distance to the rear of the stand-

ard D and forming a short handle of the center piece E, having the cross-head C secured to its upper end, its lower end being bolted 55 between the rear ends of the side bars A A. However, I prefer the method first described.

The side bars A A are preferably formed as shown in Fig. 1 of the drawings, being about three and one-half inches wide at the 60 point of connection with the standard D and tapering toward either end. They are preferably made of wood, have tenons formed on their upper ends, and should be about four feet long and three-fourths of an inch thick. 65

The wheel B is light, strong, and cheaply constructed, and possesses some novel features. It is composed of two flat pieces of wood formed to cross each other at right angles in the center of the wheel and halved or 70 boxed into each other at their central point of connection. Being made wide enough in the center of the wheel to secure strength and solidity, the radial ends are cut down to the proper size for spokes, as shown in the 75 drawings.

The rim of the wheel B is simply a tire, preferably composed of band-iron one inch wide by one-eighth of an inch thick. It is secured to the wheel by means of wood-screws 80 inserted through the tire and into the ends of the spokes. A metal hub is formed by inserting through the center of the wheel a short piece of small gas-pipe or other similar tubular metal, of sufficient length to project 85 a short distance on each side of the wheel. A washer or plate having a central aperture large enough to admit of the passage of the projecting ends of the tube is placed on each side of the center of the wheel. The projecting ends of the metal tube are then swaged or riveted down over the washers or plates, thus forming a substantial metal hub, and at the same time binding the wooden parts of the wheel immovably together, as shown at 90 F in Fig. 3 of the drawings. Should a longer hub be desired, more or thicker washers may be used; or the projecting ends of gas-pipe may be screw-threaded on their outside and nuts G screwed down on the opposite sides of the 100 wheel, as shown in Fig. 4 of the drawings. The projecting ends of the gas pipe or tube may then be allowed to extend through the nuts G any distance desired. By this con-

struction a wheel much cheaper, much lighter, and fully as serviceable and durable as the heavier and more expensive kinds in common use is secured.

- 5 The cross-head C is made of wood, is about twenty inches long, and provided in its center with a longitudinal mortise, said mortise being of such a length that when the tenoned ends of the side bars A A are inserted therein 10 they will be drawn a little closer together than they are at other points. The center piece E is formed wedge-shaped, and being placed with its narrow end above is driven upward through the mortise between the tenoned ends of the side bars A A until perfect 15 tightness is secured. The center piece E should be of sufficient length to reach about one-third of the distance from the cross-head C to the standard D. A small bolt e is inserted transversely through the side bars A A and the center piece E, which serves to 20 stiffen the frame and bind the parts immovably together.
- The standard D is preferably made of wood, 25 and should be about eighteen inches long, two inches wide from front to rear, and one and one-fourth inch thick. It should be formed with a curve, as shown in the drawings, said curve being equal to that of a circle 30 whose radius is equal to the distance from the standard D to the center of the wheel B. Formed in this manner the standard D may be adjusted high or low and the pitch of the shovel will always remain the same.
- 35 The standard D is adjustably secured between the side bars A A, as shown in Fig. 1 of the drawings, by means of the two clamping-bolts a a, one of which is made to pass through near the upper edge of the side bars 40 A A and just in front of the standard D, the other bolt a being made to pass through near the lower edge of the side bars A A and just in the rear of the standard D, as shown in Fig. 1 of the drawings.
- 45 The wheel B is secured in its place by means of a bolt b, which passes transversely through the lower ends of the side bars A A and the hub of the wheel B.
- From the construction of my improved 50 hand-plow herein shown and described it will be seen that there is no wide frame or laterally-projecting parts. Excepting the cross-head C, it is, in fact, less than three inches in lateral width in any part of its frame. It will also 55 be seen that on account of its simplicity and the material used it may be very cheaply

constructed. It is very light—not exceeding from eight to ten pounds in weight—and is strong and durable.

It is apparent that all shrinkage of the timber may be readily taken up—as, for instance, it will be seen that by tightening the nuts on the bolts e, a a, and b the side bars A A will be drawn tightly against the center piece E, the standard D, and the hub of the wheel B, 65 no matter what amount of shrinkage takes place in any of the connected parts.

Should the wooden cross-pieces in the center of the wheel become loose, they are readily tightened by further riveting the ends of 70 the hub F, as shown in Fig. 3 of the drawings, or by tightening the nuts G, if constructed on the plan shown in Fig. 4.

Should the cross-head C ever become loose, it is only necessary to withdraw the bolt e 75 and drive the wedge-shaped center piece E farther through the mortise in the cross-head C, thus spreading the tenoned ends of the side bars A A, after which the bolt e may again be inserted in its place by boring a 80 new hole through the center piece E corresponding with the holes in the side bars A A. Thus every part of the implement may always be kept tight and rigid.

Referring to Fig. 1 of the drawings, it will 85 be seen that if the nuts on the bolts a a are loosened the clampage of the side bars A A upon the standard D will be released and the said standard D may be raised or lowered, thus adapting the shovel d to run deep or 90 shallow, as may be desired, or the height of the cross-head or handle may be varied to suit the convenience of the operator. When the nuts a a are again tightened, the parts 95 will be firmly secured in their adjusted position.

What I claim, and desire to secure by Letters Patent, is—

The combination, in a hand-plow, of the side bars A, the wheel B, having a metal 100 hub or axle in its center, the standard D, secured between the side bars and the bolts a a, the cross-head C, and the center piece E, substantially as shown and described.

In testimony whereof I affix my signature 105 in the presence of two witnesses.

PETER DUNLAP GRAHAM.
